WOVEN CLOTH

Jan V. Weinberger, Truro, Nova Scotia, Canada

Application August 10, 1945, Serial No. 610,077
In Canada October 21, 1943

7 Claims. (Cl. 139—390)

1

This invention relates to cloth and the object is to provide a woven cloth having characteristics which render it especially useful as a protective covering for soldiers and others exposed to injury by bullets, shrapnel, or other flying objects.

More particularly, the invention provides a thick, dense, stretchable cloth of novel construction characterized by a high degree of tensile strength and the absence of internal voids or air spaces. These characteristics render the cloth highly resistant to penetration by bullets, shrapnel, fragmentation or other flying objects since the force of impact of such objects against the cloth is cushioned by the thickness and internal density characteristics of the cloth and also by the flexing and tensioning of the cloth which ensures that the force of impact will be distributed over and resisted by a large area of the cloth bordering the point of impact. The flexing and tensioning of the cloth also tends to deflect objects impacting thereagainst so that the effect of the impact on the body of the wearer is that of a glancing rather than a direct blow.

In its preferred embodiment the cloth of my invention comprises a plurality of courses of large gauge weftwise extending fillers bound in place and crushed together by a plurality of woven binding fabric between which the fillers are laid during the weaving operation. The fillers of each course are staggered with reference to the fillers of the next adjacent course or courses and the binding fabrics extend in sinuous or zig-zag fashion from one face of the cloth to the opposite face. The binding fabrics are complete as to warp and weft and are woven with sufficient warp tension to cause the fillers of each course to be crushed into close contact with each other and with the fillers of the adjacent course or courses. This crushing together of the fillers eliminates internal voids and air spaces and thereby produces a relatively thick cloth of exceptional density. During the weaving operation in which the fillers are laid in place therebetween, the component fabrics of the cloth are woven so that the warp threads in each fabric pass between the warp threads of the remaining fabrics at a number of points of intersection where the fabrics cross one another in passing from one face of the cloth to the opposite face. This produces a finished cloth in which each filler is substantially completely enclosed by an enveloping woven fabric covering conjointly formed by filler engaging portions of component fabrics of the cloth. The thickness of the cloth produced in accordance with this invention may be increased to any desired extent within practical limits by increasing the number of courses or fillers and the number of binding fabrics.

The invention will now be further described in

connection with the accompanying drawing, in which—

Fig. 1 is a diagram illustrating the manner in which the large gauge fillers are bound in place between a plurality of woven fabrics which extend in sinuous or zig-zag fashion from one face of the cloth to the opposite face. In this view the fillers are shown in an uncrushed condition and the binding fabrics are shown in what may be termed a relaxed or untensioned condition since the main purpose of this view is to illustrate the relative staggering of the fillers contained in adjacent courses and the manner in which the binding fabrics are trained around the fillers in passing from one face to the opposite face of the cloth.

Fig. 2 is a view similar to Fig. 1, but illustrates the manner in which the fillers are crushed together and caused to assume a triangular shape by the warp tensioning to which the binding fabrics are subjected during the weaving of the cloth.

Fig. 3 is a perspective view illustrating, more or less diagrammatically, the manner in which the warp threads of each fabric pass between the warp threads of the remaining fabrics at the points of intersection where the fabrics cross one another in passing from one face of the cloth to the other.

Referring more particularly to the drawing, my improved cloth is generally indicated at 5. It comprises two courses of fillers respectively indicated at 6 and 7 and three woven binding fabrics respectively indicated at 8, 9 and 10. The fillers 6 of one course lie adjacent one face of the cloth and are staggered with reference to the fillers 7 of the companion course which lie adjacent the opposite face of the cloth. The fillers 6 and 7 extend in the weftwise direction of the cloth and are of much larger gauge than the component warp and weft strands of the binding fabrics 8, 9 and 10. Exceptionally good results are obtained when the fillers 6 and 7 and the warp and weft strands of the woven fabrics 45 8, 9 and 10 are made exclusively of "nylon" but it is to be understood that the invention is not limited to the use of this material since any other materials having the requisite properties may be used. Each of the binding fabrics 8, 9 and 10 is 50 a complete woven fabric comprising warp strands A and weft strands B. These binding fabrics are trained around the fillers 6 and 7 as shown in the drawings so that said fabrics extend in sinuous or zig-zag fashion from one face to the 55 opposite face of the finished cloth.

During the weaving operation in which the fillers 6 and 7 are bound in place between the fabrics 8, 9 and 10, the latter are woven so that the warp strands A of each fabric pass between the warp strands A of the remaining fabrics at

a number of points of intersection where the fabrics cross one another in passing from one face to the opposite face of the cloth. This is best seen in Figs. 1 and 3. During the weaving operation the fabrics 8, 9 and 10 are placed under sufficient warp tension so that the fillers 6 and 7, which are initially of circular cross section as shown in Fig. 1, are crushed together so that they assume the triangular shape illustrated in Fig. 2. Also, as clearly illustrated in Fig. 2, the crushing of the fillers 6 and 7 by the warp tensioning of the woven fabrics 8, 9 and 10 causes the fillers of each course to be crushed into contact with each other and with the fillers of the adjacent course in such manner as to eliminate internal voids or air spaces and thereby provide a relatively thick cloth of great density. It will also be noted that the binding fabrics 8, 9 and 10 are trained around the fillers so that, in the finished cloth, each filler is substantially completely enveloped by a woven fabric covering which is conjointly formed by filler engaging portions of the three binding fabrics. As previously intimated, the invention is not restricted to the manufacture of cloth having only two courses of fillers bound in place between three binding fabrics since thicker cloths may be produced by increasing the number of courses of fillers and the number of binding fabrics employed. In the case of a cloth comprising two courses of relatively staggered, large gauge fillers and three binding fabrics the effect of the crushing action to which the fillers are subjected by the binding fabrics is to change the cross sectional shape of the fillers from the circular shape shown in Fig. 1 to the triangular shape shown in Fig. 2, thus producing a type of cloth in which the fillers, as viewed in cross section, present the appearance of similar reversely arranged triangles fitted together in closely nested relation.

The cloth produced in accordance with this invention is a relatively thick, dense cloth which is resiliently stretchable under high pressure such as that caused by the impact of a bullet or other object propelled thereagainst at relatively high velocity and is characterised by a high degree of tensile strength. The density of the cloth resulting from the manner in which the weftwise extending fillers are crushed together by the binding fabrics precludes the possibility of bullets or other objects penetrating the cloth by passing between and crowding aside the component fillers. Since the cloth is relatively thick and can be pierced only by objects forcing their way through instead of crowding aside the closely packed fillers it will be seen that this cloth has great impact cushioning properties as well as high resistance to penetration and these properties are enhanced by the stretchability and tensile strength of the cloth.

An exceptionally desirable type of protective cloth may be formed by taking two cloths made in accordance with this invention and laminating them together so that the weftwise extending fillers of one cloth are disposed at right angles to the weftwise extending fillers of the component cloth. The two cloths thus laminated may be secured together by binding threads, rivets or other suitable fastening means.

Having thus described what I now consider to

be the preferred embodiment of my invention it will be understood that various modifications may be resorted to within the scope and spirit of the appended claims.

5. I claim:

1. A woven cloth comprising a plurality of courses of large gauge weftwise extending fillers bound in place and crushed together by a plurality of intersecting woven binding fabrics.

10. 2. A woven cloth as set forth in claim 1, in which the fillers of each course are staggered with reference to the fillers of the next adjacent course or courses.

15. 3. A woven cloth as set forth in claim 1, in which the fillers of each course are staggered with reference to the fillers of the next adjacent course or courses and in which the woven binding fabrics are trained around the fillers so that each fabric repeatedly crosses each of the remaining 20 fabrics at a plurality of points of intersection and extends in zig-zag fashion from one face to the opposite face of the finished cloth.

25. 4. A woven cloth comprising a plurality of courses of large gauge weftwise extending fillers bound in place and crushed together by a plurality of intersecting woven binding fabrics, said woven fabrics extending in zig-zag fashion from one face to the opposite face of the cloth so that each fabric repeatedly crosses each of the remaining fabrics at a plurality of points of intersection where the warp strands of one fabric pass between the warp strands of the intersecting fabrics, said fabrics being woven under sufficient warp tension to cause the fillers of each course 30 to be crushed into close contact with each other and with the fillers of the next adjacent course or courses.

35. 5. A woven cloth as set forth in claim 4, characterized in that each filler is substantially completely enclosed by a woven fabric envelope conjointly formed by a plurality of said fabrics.

40. 6. A woven cloth comprising two courses of large gauge weftwise extending fillers which are bound in place and crushed together by a plurality of woven binding fabrics so that, in cross section, the two courses of fillers present the appearance of similar, reversely arranged triangles fitted together in closely nested relation, said fabrics being woven so that the warp strands of each fabric repeatedly pass between the warp strands of each of the remaining component fabrics at a plurality of spaced points of intersection where the fabrics cross in passing from one face to the opposite face of the finished cloth.

45. 7. A laminated material comprising a plurality of plies of woven cloth, each ply comprising a plurality of courses of large gauge weftwise extending fillers bound in place and crushed together by a plurality of woven fabrics which are woven so that the warp strands of each fabric repeatedly pass between the warp strands of each of the remaining component fabrics at a plurality of spaced points of intersection where the fabrics cross in passing in zig-zag fashion from one 50 face to the opposite face of the cloth, said material being further characterized in that the component plies thereof are secured together so that the weftwise extending fillers of one ply cross the weftwise extending fillers of the next adjacent 55 ply or plies.

JAN V. WEINBERGER.
